UNITED STATES PATENT OFFICE.

GRANT I. RAWSON, OF DETROIT, MICHIGAN, ASSIGNOR, BY MESNE ASSIGNMENTS, TO DIAMOND POWER SPECIALTY CORPORATION, OF DETROIT, MICHIGAN, A CORPORATION OF MICHIGAN.

DRAIN VALVE FOR BOILER CLEANERS.

Application filed March 7, 1921. Serial No. 450,413.

The invention relates to new and useful improvements in a drain valve for boiler cleaners adapted for use particularly with those boiler cleaners in which steam is ejected from blower units for cleaning the soot and ashes from boiler tubes.

An object of the invention is to provide, in connection with boiler cleaners of this class, a simple and effective means of insuring the draining of the pipes connected with the boiler cleaner previous to the blowing operation.

Another object is the provision of thermostatic means for opening and closing the drain valve.

Another object is the provision, in connection with a boiler cleaner of this class, of means for employing the liquid contained in the piping of the blower system for opening a drain valve.

Other objects will appear hereinafter.

The invention consists of the combinations and arrangements of parts hereinafter described and claimed.

The invention will be best understood by reference to the accompanying drawings, which form a part of this specification and in which,

Fig. 1 is an elevational view of the invention,

Fig. 2 is a central sectional view of a portion of the valve used in the invention.

In boiler cleaners in the class with which the invention is adaptable for use, a header 7 communicates with a suitable source of steam supply. Connected to this header and communicating with the blower units, which are positioned within the settings of the boiler, are delivery pipes 8, each of which communicates with its respective blower unit. Positioned in each of the pipes 8 is a suitable valve 9 for controlling the delivery of the cleaning fluid or steam to the blower unit. When it is desired to clean the boiler, steam is delivered to the header 7. As each unit is called into operation there is a respective control valve 9 opened to deliver steam to the unit. After the blowing process, these valves are closed as is likewise the valve which controls the delivery of steam to the header 7. The steam which is remaining in the header 7 and the pipes connecting therewith, between blowing periods, condenses to form liquid. When

the next blowing period arrives, unless this liquid is first removed from the pipes, the same will be discharged against the boiler tubes, thereby serving to cake the soot and ashes upon the tubes. To eliminate this difficulty and to insure the removal of all the liquid from the pipes before the blowing process takes place, I have provided a novel drain valve, which will be automatic in its action.

Communicating with the header 7 is a drain pipe 10, which is connected by a suitable coupling 11 to one end of a pipe 12, the opposite end of which is threaded into a leg 13 of the base-forming member 14. A pipe 15 is threaded into the leg 13 and serves as a continuation of the pipe 12. This pipe 15 is formed preferably of copper or some other material which has a high co-efficient of expansion. This pipe 15 passes through an opening formed in the leg 13' so as to permit slidable movement of the pipe 15 in this opening. This pipe is connected by suitable piping so as to serve as a drain pipe for the header 7 and the connected pipes. Interposed in these connecting pipes is a valve 16, the valve stem 23 of which projects into a housing 18. This housing 18 is provided with a suitable cap 19, which is secured to the body of the housing by suitable bolts. Positioned in the housing 18 and rigidly attached to the valve stem 23, adjacent its upper end, is a piston 20, which is provided on its periphery with suitable packing or piston rings 21. Communicating with the header 7 is a pipe 17, which communicates through the cap 19 with the interior of housing 18. Positioned within the housing 18 and embracing the valve stem 23 is a spiral spring 22, one end of which engages the lower portion of housing 18 and the other end of which engages the piston 20, thereby serving to maintain the piston 20 positioned adjacent the upper end of the housing 18. When the piston 20 is at the position shown in Figure 2, the valve 16 is in open position. In order to close the valve 16, it is necessary to move the valve stem downward relative to the housing 18. Consequently, since the piston 20 is rigidly attached to the valve stem, the spiral spring 22 will be in compressed position when the valve is closed. Communicating with the interior of housing 18 is a pipe 24, which

communicates with the pipe 17, a valve 25 (not shown) being interposed in the pipe 24. A pipe 26 serves to form communication between the pipe 24 and a valve 27 (not shown).

Pivottally mounted on base 14 is an arm 28, which is pivotally connected by an arm 29 to a collar 30, which is rigidly fastened upon the pipe 15. A suitable turnbuckle 31 is interpositioned in the arm 29 for the purpose of adjusting the length of said arm.

When it is desired to clean the boilers, the steam is first turned into the header 7. Any liquid which has accumulated in the header 7 will be forced through the pipe 15. When the liquid strikes the pipe 15, a cooling of the same takes place with a quick contraction thereof. As the steam flows into the header 7, it also passes through the pipe 17 and into the housing 18, thus forcing the valve 16 into closed position by moving the piston 20 downwardly in the housing 18.

It is to be noted that a bleed passage is formed in the piston 20 to prevent too rapid movement of the same when the steam enters the housing 18. Upon the contraction of the pipe 15, the arm 28 is caused to swing so that the free end thereof forces the valve stem 32 inwardly, thereby opening the valve 25 and permitting the flow of steam through the pipe 24 into the housing 18. As soon as the steam is permitted to enter the housing 18 through the pipe 24, the steam pressure at opposite sides of the piston 20 becomes equalized and the piston 20 moves upwardly relative to the housing 18 in response to the pressure of the spring 22, thereby opening the valve 16. The liquid, which has flowed into the pipe 15, is thereby permitted to escape through the drain pipe 12. Following the liquid in its flow through pipe 15 is the steam which has been turned into the header 7. When this steam passes into the pipe 15, an expansion of the pipe takes place with a consequential swinging of the arm 28 in the opposite direction to engage the valve stem 33, causing the same to open the exhaust valve 27. When the arm 28 disengages from the member 32, a spring (not shown) causes the valve 25 to close. The flow of the steam, therefore, is prevented from entering the housing 18 through the piping 24 and the disc 20 is forced downwardly so that the valve 16 closes. The steam, which has been delivered to the housing 18 through the piping 24, is permitted to escape through the pipe 24 and the exhaust valve 27. In order to regulate the distance of movement of the piston 20, an adjusting screw 35 is threaded into the cap 19, as will be readily understood. It is to be noted that the valves 27 and 25 are supported by a suitable supporting member 34, which is secured to the base 14.

While I have illustrated and described the preferred form of my invention, I do not wish to be limited to the specific details of construction, but desire to avail myself to such modifications and changes as come within the scope of the appended claims.

Having thus described my invention what I claim as new and desire to secure by Letters Patent is:

1. In a drain system for boiler cleaners, a drain valve; an auxiliary valve for controlling the operation of said drain valve; and thermostatic means for regulating the operation of said auxiliary valve. 80

2. In a drain system for boiler cleaners, a drain valve; an auxiliary member for controlling the operation of said drain valve; an expansible and contractile member; and means cooperating with said expansible and extractile member for operating said auxiliary member. 85

3. In a drain system for boiler cleaners, a drain valve; an expansible and contractile member; a pivotally mounted member connected to said expansible member; and means operable by said pivotally mounted member for controlling the opening and closing said valve. 90

4. In a boiler cleaner drain system, a drain valve; an expansible and contractile member; a pivotally mounted member connected to said expansible and contractile member; means operatively connected to said drain valve for opening and closing the same and means operable by said pivotally mounted member for controlling the operation of said opening and closing means. 95

5. In a drain system for boiler cleaners, a drain valve; an expansible and contractile member; a pivotally mounted arm connected to said expansible member; means for opening and closing said valve; means for delivering a fluid to said opening and closing means; and means, operable by said arm, for controlling the delivery of fluid to said opening and closing means by the fluid delivery means. 100

6. In a drain system for boiler cleaners, a drain valve, fluid operated control means for said valve, and thermostatic means for controlling the operation of said fluid operated means. 115

7. In a drain system for boiler cleaners, a drain valve, means for controlling the application of fluid pressure to shift said valve, a drain pipe controlled by said valve, and means operable by temperature variations in said pipe controlling the operation of the first named means for causing the shifting of said valve. 120

8. In a drain system for boiler cleaners, a drain valve, an expansible and contractile pipe forming a drainage passage leading to said valve, and mechanism connected to said 130

pipe for controlling the operation of said valve and effecting a relatively large travel of the valve for a given expansion or contraction of said pipe.

5. 9. In a drain system for boiler cleaners, a drain valve, fluid operable control means for said valve, a pipe in open communication

with the drain system for applying fluid pressure to said valve tending to close the same, an auxiliary valve for controlling an application of fluid force to said valve for opening the same, and thermostatic control means for said auxiliary valve.

GRANT I. RAWSON.
